UNITED STATES PATENT OFFICE.

GEORGE W. PERKINS, OF BOSTON, MASSACHUSETTS, ASSIGNOR TO HEATON PENINSULAR BUTTON FASTENER COMPANY, OF BOSTON, MASSACHUSETTS, A CORPORATION OF MAINE.

BUTTON-FASTENING MACHINE.

1,089,344.

Specification of Letters Patent.

Patented Mar. 3, 1914.

Application filed July 1, 1912. Serial No. 706,909.

To all whom it may concern:

Be it known that I, GEORGE W. PERKINS, citizen of the United States, residing at Boston, county of Suffolk, State of Massachusetts, have invented a certain new and useful Improvement in Button-Fastening Machines, of which the following is a specification, reference being had therein to the accompanying drawings.

10 The invention relates to a machine for attaching buttons to shoes and other articles by metallic fasteners, and is especially intended for that class of such machines in which the metallic fastener is formed from 15 a wire which is fed through the eye of the button, the wire then being formed into the shape for the fastener, the button and attached wire then being carried to position for the fastener to be secured to the shoe 20 or other article.

The invention relates especially to means for pushing or removing the buttons from the raceway one at a time to the position where it receives the wire through the eye 25 of the button and to the means for holding the button in position while it is being threaded.

The invention will be fully understood from the following description taken in 30 connection with the accompanying drawings, and the novel features thereof will be pointed out and clearly defined in the claims at the close of this specification.

In the drawings, Figure 1 is a side elevation of a portion of a raceway and connected parts, together with an attachment embodying the invention and showing a portion of the operative parts necessary to illustrate the invention, the parts being 40 shown in the position where the button has been carried under the placer. Fig. 2 is a side elevation of the parts shown in Fig. 1 after the slide has descended to carry a button with attached fastener to the anvil and 45 the push member has been withdrawn into position ready to be carried forward to push another button from the raceway beneath the placer and the placer has been raised to admit the button when pushed forward. Fig. 3 is a view of the parts shown in the position of Fig. 1 looking in the direction of the arrow. Fig. 4 is a sectional view partly broken away to show more clearly the undulated form of the button 55 seat at the lower end of the raceway.

Referring now to the drawings: 1 represents the raceway and 2 the raceway cover, the buttons traveling down the raceway with the eyes of the buttons in the groove of the raceway in the usual manner. Any 60 suitable form of mechanism for feeding the wire through the eye of the button and forming the loop and legs of the fastener and severing the blank for the fastener from the length of wire may be employed, 65 one form of said mechanism being shown and described in Patent No. 982,440, dated January 24, 1911, granted on my application, and it is not deemed necessary to show such mechanism in detail. In the accompanying drawings of the present application a portion of the mechanism for forming the fastener is shown similar to the mechanism shown in said patent.

3 is an arbor on which the wire 4 rests 75 after it has been threaded through the eye 5 of the button 6.

7 is what is termed the former which forms the loop of the fastener and is attached to a former holder 8 which is reciprocated by an arm 9 carried by a lever 10 which is actuated by suitable mechanism, not shown, said arm 9 engaging with a slot 11 in the former holder. The legs of the fastener are formed by a slide 12 which is 80 actuated by an arm 13 carried by a lever 14, said arm 13 engaging with an elongated slot 15 in the slide 12. Means for actuating said levers 10 and 14 is fully shown and described in said patent above mentioned. 90

When the button is in the position for receiving the wire for the fastener, as shown in Fig. 1, means should be provided for holding the button against movement during the feeding of the wire and forming of 95 the fastener. The means which I have provided are as follows: A plate or block 16 is formed with a cupped out under side which is adapted to fit over the head of the button and is mounted on a reciprocable or 100 movable rod 17 which may be moved down to clamp the button at the proper time and which may be lifted to release the button after the fastener is formed. Said rod 17 is connected with a lever 18 which is actuated and controlled in the manner to be hereinafter described. Said lever 18 is pivoted at 19 to a fixed part of the machine. In the form of construction shown the lower 105 end of the lever is bifurcated vertically to 110

straddle a block 57 which is loose on the rod 17 and is also laterally bifurcated forming ears between which a pin 20 projects from both sides of the block 57 to engage with the said ears and form a connection with the said lever 18. The elongated recess 21 between the ears 22—22 allows play for the pins 20 during the rocking movement of the lever 18. A spring 23 coiled around the rod 17 between the block 57 and the placer block 16 enables the lever 18 to move the placer down with a yielding pressure upon the button. A slidable push rod 24 is mounted in and slidable in an apertured bracket 25 affixed to the frame of the machine in such manner that said push rod 24 is inclined at an angle to the raceway and is adapted to be projected down through the slotted forward end of the cover 2 to engage with the head of a button in the lower part of the raceway and to push it out of the raceway beneath the placer 16. A finger 26 pivoted at 27 projects through the cover of the raceway to prevent the button from sliding out of the raceway of its own weight, being given sufficient tension for that purpose by a spring 28 which yields, however, so that the finger may be turned upward out of the path of the button by the pressure of the push rod 24 when the push rod 24 is actuated.

When the parts are in the position shown in Fig. 1 with the former and former holder 8 retracted, the bent rear arm of the lever 18 rests upon the upper face of the former holder 8, thereby holding the lever 18 in position where its forward end is turned down to hold the placer in engagement with the head of the button. When the former and former holder move down to the position shown in Fig. 2 the former holder rides down out of engagement with the rear arm of the lever 18 allowing said lever to be turned on its pivot by the spring 45, lifting the lower arm of the lever and turning down the rear arm of the lever, as shown in Fig. 2.

A lever 29 is pivoted at 30 and is bifurcated forming a slot 31 with which a pin 32 projecting from the slide rod 24 engages. Said lever 29 is formed with an elongated slot 33 with which there engages a pin 34 which projects from a slide bar 35 so that when said slide bar 35 is moved either forward or back it rocks said lever 29 and thereby actuates the push rod 24. Said slide bar 35 is formed with an elongated slot 36 with which a guide pin 37 engages to guide and limit the movement of said slide bar. A spring 38 has one end secured to the lower end of the slide bar 35, the other end of said spring being secured to a fixed support 39, said spring normally tending to retain the slide bar 35 in the most forward position shown in Fig. 2 with the stud 37 engaging the rear end of the slot 36. When

said slide bar 35 is moved backward it expands the spring 38, as shown in Fig. 1 and when the backward pull or detent upon the slide bar is released said spring 38 will pull the slide bar 35 forward again.

A dog 40 is pivoted at 41 to the slide bar 35 and is formed with a tooth 42. Said dog is formed with a curved slot 43 with which a pin 44 which projects from the side of the raceway engages. The form of the slot is such that when the slide bar 35 is in its rearmost position, shown in Fig. 1, the dog 40 may be turned up with its tooth 42 bearing against the upper face of the former holder 8. A spring 45 has its lower end secured to the frame and its upper end secured to the lever 18 which exerts a downward pull on the rear arm of the lever 18 and when the former holder 8 moves downward far enough for the former holder to ride out from under the rear arm of the lever 18 said spring will pull the rear arm of said lever 18 down, thereby turning said lever on its pivot and raising the forward end of said lever and thereby raising the placer 16. When the former holder continues its downward movement far enough to ride past the tooth 42 then the spring 38 will be permitted to pull the slide 35 downward thereby causing the dog 40 to be turned down into the position shown in Fig. 2 by reason of the pin 44 engaging with the curved slot 43 and thus bring the tooth 42 of the dog down behind the rear end of the former holder 8, as shown in Fig. 2. When the slide 35 thus moves downward it turns the lever 29 backward thereby retracting the push rod 24, as previously described, the placer 16 being still in the raised position. When the former holder 8 and its attached former 7 move rearward or upward, as we term it, the rear end of the former by its engagement with the tooth 42 will turn the dog 40 up on its pivot and also cause the retraction of the slide 35 until the tooth 42 rides up onto the upper side of the former holder 8 after which the continued rearward movement of the former will not further move the slide 35. During said initial rearward movement of the former and the rearward movement of the slide 35 the lever 29 will be turned down thereby pushing forward the rod 24 which in so doing will push forward the button which had previously slid down the raceway into position beneath the forward end of the push rod and in engagement with the detent 26. This downward push movement of the rod 24 will be sufficient to overcome the tension of the detent 26 and push the button into position beneath the placer 16. The button when thus positioned beneath the placer will come into engagement with a detent 55 which is pivoted at 46 and which is held by a spring 47 with a yielding pressure

against the button to prevent the button from passing out before it is clamped by the placer. The continued rearward movement of the former holder after it has actuated the dog 40 will bring it into engagement with the rear arm of the lever 18 which projects into the path of the former holder 8 and thereby turns the lever 18 by lifting the rear arm thereof and turning down the forward arm, so that the placer 16 is brought into engagement with the head of the button, clamping it firmly upon the plate 56 and holds it there during the spreading of the wire and forming of the fastener.

When the former moves forward again the former holder will first ride down out of engagement with the rear arm of the lever 18, allowing the rear arm of the lever 20 to be pulled down by the spring 45 thereby raising the placer from engagement with the button, then the former holder will move down far enough to clear the tooth of the dog 40, so that the slide 35 will be moved 25 forward and thereby turn the lever 29 so as to retract the push rod and the button attached to the fastener is now free to be carried down by the proper mechanism to bring the button and attached fastener to 30 the fabric 48 upon the anvil 49. This carrying down of the button and attached fastener is accomplished by the downward movement of the slide 12 under actuation of the lever 14, arm 13 and spring 50. Mechanism for thus actuating the slide is fully 35 described in said patent previously mentioned and it is not deemed necessary to show or fully describe the same herein.

In order to afford sufficient clearance between the head of the button which is engaged by the push rod and the button immediately behind it, so that the push rod in pushing the advance button into its position beneath the placer will not be interfered 40 with by the following button, the lower part of the raceway on which the lowermost button rests is preferably formed with a hump 45 and a depressed portion at the rear of the hump portion, so that the foremost button will be elevated slightly above the following button and thereby when the push rod descends it will be clear of interference 50 with the head of said following button as will be apparent from the drawings. The 55 cover of the raceway should also have a curve corresponding with the hump and depression in the raceway.

Secured to the side of the lever 18 is an adjustable stop screw 58 which is adapted 60 to strike against the raceway plate 56 to limit the rocking movement of the lever 18, and thereby limit the upward stroke of the placer.

Starting with the parts in the position 65 shown in Fig. 1 the operation will be as

follows: The wire has been threaded through the eye of the button. The parts are now in position for the downward movement of the former and slide under the actuation of the levers 10 and 14. First the 70 lever 10 pushes down the former and forms the loop of the fastener, then the lever 14 will, after the arm 13 has traveled to the end of the slot 15, carry down the slide 12 and form the legs of the fastener after which 75 the continued movement of the slide will carry the button to the material on the anvil, as shown in Fig. 2, and will drive the legs of the fastener through the material on the anvil. During this downward movement 80 of the former and slide the lever 18 will be turned to release the placer from the button so that it can be carried down by the slide and the push rod 24 will also be retracted so that another button may come 85 down into position to be engaged by the push rod, being held in such position by the 90 detent 26. Then on the return stroke of the former the dog 40 will be turned up by the former 95 8, thereby actuating the slide 35 to cause the rod 24 to push the button into position beneath the placer. Then the placer will come down to clamp the button ready for the next downward stroke of the former and slide.

What I claim is:

1. In a button fastening machine, a button raceway, a push member reciprocable in a path at an angle to the path of movement of the buttons in the raceway, the paths of movement of the push member and of the buttons being in the same plane and intersecting each other, means for actuating the push member whereby it engages one of the buttons in the raceway and positions it for receiving a fastener wire, means for clamping the button in its position to receive the fastener wire, means for moving the button and attached fastener, and means whereby the movements of the push member and clamp are controlled by the mechanism 100 which moves the button and attached fastener.

2. In a button fastening machine, a button raceway, means for pushing the lowermost button out of the raceway into position for receiving a fastener, and means for clamping the button in its position for the fastener, the raceway being formed with an undulation near its lower end to support the button which is engaged by the push member at a higher elevation than the next following button.

3. In a button fastening machine, a button raceway, a reciprocable push member for pushing a button out of the raceway into position to receive a fastener wire, a reciprocable member which forms the fastener, and means controlled by the said reciprocable fastener mechanism on its forward movement which retracts the said 125 130

push member, said fastener forming mechanism on its forward movement forming the fastener for a previously positioned button, and on its retrograde movement actuating the push member to eject another button from the raceway and to position it for a fastener.

4. In a button fastening machine of the character described, a reciprocable member which forms a fastener out of a wire, a button raceway, a push member for pushing a button out of the raceway into position to receive a fastener wire, means whereby the button is clamped in its placed position for the wire, and means whereby the reciprocable fastener forming mechanism controls the movements of the push member and of the clamp.

5. In a button fastening machine, a button raceway, a reciprocable push member mounted over the raceway and movable in a path at an angle to the path of movement of the buttons in the raceway, a pivoted lever connected with said push member, a reciprocable slide member connected with said lever whereby said lever is rocked on its fulcrum, a reciprocable former which forms a wire for a fastener, and mechanism connected with the lever rocking slide which is actuated by the movement of the reciprocable former whereby the rocking lever and push member are actuated to push a button out of the raceway.

6. In a button fastening machine, a button raceway, a reciprocable push member mounted over the raceway and movable in a path at an angle to the path of movement of the buttons in the raceway, a pivoted le-

ver connected with said push member, a reciprocable slide member connected with said lever whereby said lever is rocked on its fulcrum, a reciprocable former which forms a wire for a fastener, and mechanism connected with the lever rocking slide which is actuated by the movement of the reciprocable former whereby the rocking lever and push member are actuated to push a button out of the raceway, a movable placer which clamps the button in position to receive a fastener wire after it leaves the raceway, and mechanism actuated by the reciprocable former to actuate the said placer clamp after the push member has ejected the button from the raceway.

7. In a button fastening machine, a button raceway, a movable placer clamp which is adapted to clamp a button to receive a fastener, a reciprocable push member adapted to push the lowermost button out of the raceway to a position beneath the placer clamp, a lever which is connected with the said placer clamp, a reciprocable member which forms a wire fastener, and mechanism whereby the retrograde movement of the former actuates the push member to push a button from the raceway into position to receive a fastener wire and then actuates the clamp to hold the button in its position for the fastener wire.

In testimony whereof I affix my signature, in presence of two witnesses.

GEORGE W. PERKINS.
